UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

HEADLIGHT.

Application filed February 5, 1921. Serial No. 442,638.

To all whom it may concern:

Be it known that I, CHARLES E. GODLEY, a citizen of the United States, and residing at Detroit, in the county of Wayne and State of Michigan, have invented a new and Improved Headlight, of which the following is a specification.

This invention relates to the construction of headlights adapted for use on automobiles, launches and wherever else lamps with projecting reflectors may be desired, and its object is to provide a lamp of this character whose lens ring or holder is entirely within the open end of the lamp body.

This invention consists in a cup-shaped body having its edge turned inwardly and then rearwardly to constitute a substantially cylindrical flange, and a lens holder fitting within this re-entrant cylindrical flange on the body.

It also consists in a body and a lens holder of this character provided with inclined members which interlock to secure the lens holder in position when the lens holder is rotated within the body.

It further consists in the details of construction illustrated in the accompanying drawing and particularly pointed out in the claims.

In the drawing, Fig. 1 is a vertical central section of the front edge of the body and of the lens holder mounted thereon. Fig. 2 is a front elevation of this lamp with the lens holder removed. Fig. 3 is a similar view of the body alone. Figs. 4 and 5 are sections on the lines 4-4 and 5-5 of Fig. 3. Fig. 6 is a side elevation of a portion of the lens holder. Fig. 7 is an inside elevation of a portion of the lens holder. Fig. 8 is a section on the line 8-8 of Fig. 7.

Similar reference characters refer to like parts throughout the several views.

In the large majority of headlights, the lens holder fits around the outside of the edge of the cup-shaped body, and, when the lamp is damaged, it is often impossible to remove the lens holder. The present lens holder is entirely within the re-entrant end of the lamp body and it requires practically entire destruction of the lamp to prevent the lens holder being removed. Furthermore, the present construction is of distinctive and very pleasing appearance.

The lamp body 1 is formed with a cylindrical end 2, a radial flange 3, a cylindrical

flange 4, and a second radial flange 5 which preferably terminates in a curved lip 6. These parts 2 to 6 inclusive constitute the re-entrant end of the body. While this structure might be formed from a single piece of sheet metal, I prefer to form it of two parts joined by welding or brazing at the outer or inner edges of the radial flange 3. The second radial flange 5 may be formed with holes 7 to receive the small tongues 8 on the arched springs 9.

A reflector 12 within the body has a radial extension 13 provided with a groove to receive the packing ring 15, a cylindrical flange 16 and a radial flange 17 which fits slidably within the cylindrical flange 4 of the body and contacts with the springs 9. The lens holder consists of a cylindrical portion 19 and an inwardly and rearwardly inclined portion 20 whose inner edge contacts with the lens 22. Small fingers 23 may be struck up from the cylindrical portion 19 to hold the lens in position. The cylindrical portion 19 is formed with pressed in or recessed portions 24, Figs. 6 and 7, concentric with the main portion 19, and from these portions 24 the outwardly extending locking members A shown in Fig. 6 are struck up, and consist of the inclined portions 25 and the shoulders 26.

Extending inwardly from the cylindrical flange 4 of the body are ribs or flanges B consisting of inclined portions 27, rounded shoulders 28 and straight portions 29, and adjacent thereto are the small tongues 30 which serve as stops for the locking members on the lens holder. These recessed portions 24 on the lens holder are set back sufficiently to permit the locking ribs and stops on the flange 4 of the body to pass in freely. The flange 17 of the reflector is cut away at 31, Fig. 2, to permit these ribs and stops on the body to pass, and after the reflector has been pressed inwardly against the tension of the springs 9 and turned, it will be kept in position by these stops 30, as indicated in Fig. 4.

When the lens holder is inserted into the body, the cylindrical portion 19 guides the holder within the flange 4 until the lens engages the packing 15, the ribs B and stops 30 being within the depressed portions 24 of the lens holder. The lens holder is pushed in still farther and turned until the inclined portions 25 of the parts A slide on

the inclined portions 27 of the ribs B, which draws the lens holder still farther into the body and against the pressure of the springs 9. When the shoulders 26 on the parts A 5 have passed the shoulders 28 on the ribs B, the springs will prevent reverse rotation of the lens holder in the body and the small stops 30 will limit the rotation in that direction. The springs 9 resting on the flange 10 5 of the body press against the flange 17 on the reflector, the packing 15 presses against the lens, the lens presses against the part 20 of the lens holder, and the locking members A on the lens holder press out 15 against the ribs B on the body so that rattling is prevented at all points.

The particular conformation of the forward end of the lamp body has nothing to do with the present invention and may be 20 changed as desired so long as an opening is provided to receive the lens holder of such size and shape that the lens holder is freely 25 slideable in such opening. I prefer to so form the end of the body and the lens holder 30 that when the parts 32 are assembled the radial flange 3 and the adjacent part of the lens holder will be substantially in the same plane.

It is evident that the construction of the 35 locking devices for retaining the lens holder in position may also be modified to suit the ideas of those skilled in the art without departing from the spirit of my invention as set forth in the following claims.

35 I claim:—

1. in a headlight, a sheet metal body having an opening and the metal of the body around the opening being bent radially inwardly and then rearwardly to constitute 40 an interior cylindrical flange, a lens holder rotatably mounted within the opening in the body and embodying a portion extending within said cylindrical flange, and means between the lens holder and the cylindrical 45 flange to secure the lens holder in position so that its outer portion will be practically in the plane of the radial end of the lamp body.

2. In a headlight, a sheet metal body 50 having an opening and the metal of the body around the opening being curved in-

wardly to constitute an interior cylindrical flange, a lens holder rotatably mounted within the opening in the body, and means to secure the lens holder in position, comprising inclined engaging members attached to the lens holder and to the cylindrical flange of the body. 55

3. In a headlight, a sheet metal body having an open end embodying cylindrical outer and inner portions and a radial portion connecting them, a lens holder entirely within the body and having a radial outer portion in the plane of the radial portion of the body, and means to secure the lens holder in position. 60

4. In a headlight, a body having a cylindrical opening and a cylindrical flange surrounding the opening, locking ribs extending inwardly from said flange, a lens holder having a cylindrical body provided with recesses to receive the locking ribs on the body and locking members extending outwardly in said recesses and adapted to engage the ribs on the body to secure the lens 75 holder in the body. 70

5. In a headlight, a body having an opening, a radial internally extending flange at the opening and a cylindrical flange extending rearwardly from the inner edge of the radial flange, both flanges being integral with the body, a lens holder rotatable within the cylindrical flange and having its outer edge in the plane of said radial flange on the body, and means to secure the lens holder in 80 the body. 85

6. In a headlight, a body having an opening, a radial internally extending flange at the opening and a cylindrical flange extending rearwardly from the inner edge of the radial flange, a lens holder rotatable within the cylindrical flange and having its outer edge in the plane of said radial flange on the body, and means to secure the lens holder in the body, comprising engaging members on both the lens holder and the cylindrical flange of the body, said engaging members having inclined engaging surfaces and rounded shoulders to prevent return movement of the lens holder. 95

CHARLES E. GODLEY.
